STOKER PIPE

Harold T. Blum, Glenmont, Ohio, assignor to
 Briar Hill Corporation, Millersburg, Ohio, a
 corporation of Ohio

Application April 8, 1939, Serial No. 266,850

2 Claims. (Cl. 131—181)

The invention hereinafter described is an improvement in smoking pipe structures and relates more particularly to smoking pipes having a tobacco stoking arrangement forming a part 5 thereof.

The present invention is a continuation in part of the invention shown and described in my co-pending application Serial 258,060, filed February 23, 1939.

10 It is the principal object of the present invention to provide a smoking pipe structure having a tobacco stoking means incorporated therein, which pipe structure may be economically produced.

15 A further object of the present invention is to provide a pipe smoking structure having an arrangement for controlling the firing of tobacco therein, which structure can be quickly and simply assembled or disassembled, as desired.

20 A further important object of the present invention is to provide a smoking pipe structure so arranged as to permit the user thereof to control the amount of oxygen being supplied to the tobacco being consumed and, at the same time, 25 providing a relatively cool passage for the smoke from said consumed tobacco to the mouth of the user thereof.

Another object of the present invention is to provide a smoking pipe structure wherein the 30 smoke from the tobacco being consumed is drawn away by suction on the mouthpiece, without passing through the remaining body of the tobacco within the pipe.

Further objects of the present invention will 35 be pointed out in the accompanying drawing and the following detailed description thereon and still further objects will be obvious from a consideration thereof.

In the accompanying drawing:

40 Fig. 1 is a side elevation of a pipe structure comprising the present invention having a broken away section for viewing the interior of a portion thereof.

45 Fig. 2 is an enlarged detail side cross sectional view of the bowl portion of the pipe shown in Fig. 1.

Fig. 3 is an enlarged detail side cross sectional view of the said bowl portion similar to that shown in Fig. 2 but having the tobacco controlling members in their closed or nestled 50 position.

Fig. 4 is an enlarged detail top cross sectional view of said bowl portion of the pipe taken on line 4—4 of Fig. 2.

55 Fig. 5 is a further enlarged detail top cross sec-

tional view of said bowl portion of the pipe but is taken on line 5—5 of Fig. 2.

Fig. 6 is an enlarged side view of a tubular member forming a part of the present pipe structure and having a portion thereof broken away 5 to show its interior or bore, and

Fig. 7 is a top cross sectional view of said tubular member taken on line 7—7 of Fig. 6.

Referring now more particularly to the accompanying drawing wherein like reference characters designate similar members of the present invention, reference numeral 1 refers to a pipe mouthpiece having a longitudinal bore 2 formed therethrough from end to end thereof, while numeral 3 designates a stepped end portion of 10 said mouthpiece 1 having threads formed upon the periphery thereof. The threads of the periphery of stepped portion 3 are shown in engagement with threads formed upon the interior face of stem portion 4, which stem portion 4 is formed 20 as a part of a bowl 5.

The bowl 5 may be formed, by way of example, from natural brier-wood, meerschaum and like bowl-forming materials, or may also be molded from brier-wood or meerschaum compositions. 25 Said bowl 5 has a bore 8 formed in the top end portion thereof, which bore tapers outwardly as at 7 into an enlarged chamber 6, while the opposite end of said bowl has an opening 16 formed therethrough which opens into said chamber 6 30 and is substantially in line with bore 8. Chamber 6 is connected with the interior or bore of stem portion 4 and is thereby connected to the longitudinal bore 2 of the mouthpiece 1. Further, chamber 6 has a series of projections 9 formed 35 therewith and extending therefrom.

Inserted and mounted through opening 16 and having a tight but detachable fit with the wall thereof is a tubular member 12 which is preferably formed from a lightweight metal, as by way 40 of example, aluminum. The lower end of tubular member 12 has an annular flange 15 formed therewith and extending perpendicular thereto. Said flange 15 is substantially disc-shaped due to a centrally located opening 33 formed therethrough. The opposite or upper end of tubular member 12 has the top edge 13 thereof tapered, that is, slanting from the bore downwardly towards the periphery thereof. The bore of tubular member 12 is substantially decagonal from a 50 cross sectional view, as shown in Fig. 7 of the drawing, due to the said bore being formed by a series of walls 14 which are angularly joined to one another.

A coating 34 of either carbon or meerschaum 55

is positioned upon the exterior face of tubular member 12. This coating is applied thereto by painting either a liquid carbon or a meerschaum paste upon the exterior face of said member and thereby providing both a protective coating for the metallic surface of the tubular member as well as a moisture-absorbing member within the smoke passage of the pipe structure. In this manner, the smoke is filtered and at the same time, assured of passage through the pipe structure without direct contact with metal, thereby preventing the presentation to the user of a metallic tasting smoke.

A nest of telescopic sections which are in threaded engagement with one another is mounted within the tubular member 12 and through opening 33 of flange 15. Said nest of telescopic sections is composed of sections 20, 21, 22, 23, 24 and 25, all of which are of an equal length and have a diameter sufficient to permit the sections to each fit within the bore of the next larger section thereto, that is, section 20 has a diameter substantially equivalent to the diameter of the bore of section 21 and, likewise, the diameters of sections 21, 22, 23 and 24 are respectively substantially equivalent to the diameters of the bores of sections 22, 23, 24 and 25. Sections 20, 21, 22, 23 and 24 have lefthand threads 28 formed upon the peripheries thereof with the bottom portions of said peripheries formed blank as at 31. The bores of sections 21, 22, 23, 24 and 25 have lefthand threads 29 formed upon the upper portion of the face thereof, which threads 29 are in engagement with said threads 28, thereby threadedly engaging the sections one with the other. Section 25 has an annular flange 26 extending perpendicularly therefrom which is mounted upon flange 15 and retains section 25 with its connected sections within the tubular member 12. The portion of section 25 extending outwardly from opening 33 has righthand threads 27 formed upon a periphery thereof to which is screwed a cap 30, which cap prevents the inward movement of section 25 and closes the lower end of the bore of section 25 and the other sections when in their nestled position, as shown in Fig. 3, but at the same time, cooperates with flange 26 to permit section 25 to be rotatably supported at all times by flange 15.

Said nest of telescopic sections are connected to one another by inserting the section of the smallest diameter through the lower end of the next larger section until the threads 28 and 29 thereof are in engagement and said next larger section is inserted through the lower end of the bore of its next larger section and this procedure is carried out until all of the sections are mounted within the bore of section 25. At this time, section 20 is screwed within the projecting portion 10 of a disc 17, thereby connecting said disc 17 to the telescopic sections. Disc 17 has a series of angularly joined walls 18 formed upon the edge thereof giving it a decagonal peripheral configuration similar to the cross sectional configuration of the bore of tubular member 12. As best shown in Fig. 3, said disc 17 has attached thereto a meerschaum cap 32 covering the upper face of the disc.

In assembling the present pipe structure, tubular member 12 is inserted within opening 16 of bowl 5 until flange 15 contacts the outer face of bowl 5 and thereby prevents the further insertion of the tubular member 12 within chamber 6 and tapered portion 7. During the insertion of tubular member 12 within opening 16,

the upper portion of the tubular member will also be inserted past the ends of the series of projections 9 and will thereby be retained in a spaced relation from the wall of chamber 6 and slanting portion 7. Tapered edge 13 of tubular member 12 will form a passageway with the wall of tapered portion 7 and will be assisted in maintaining this passageway due to flange 15 and projections 9. The passageway between edge 13 and the wall of tapered portion 7 can be formed narrow in order to prevent tobacco from sliding therein while, at the same time, readily permitting the passage of smoke therethrough.

The nest of telescopic sections and disc 17 can be inserted within the bore 8 of the bowl 5 downwardly into and within tubular member 12 until flange 26 of section 25 contacts the inner face of flange 15 of tubular member 12, at which time the cap 30, by a right hand rotation thereof, is screwed onto the section 25 for retaining the same and its connected members within tubular member 12. It is obvious that the nest of sections and disc 17 can be inserted within chamber 6, by way of either bore 8 or opening 16, before the insertion therein of tubular member 12 or disc 17 and the telescopic sections can be inserted with tubular member 12. By a reversal of the foregoing procedure, the members can be rapidly and readily disassembled for cleaning or like attention.

When it is found desirable, any suitable filter 11 may be placed within the bore of stem portion 4 for removing the heavy oils, tars and moistures from the tobacco smoke passing through said bore to the bore of mouthpiece 1.

In operating the present device, after the same has been assembled, the user thereof should place within the bore of tubular member 12 and bore 8 of bowl 5, both bores of which are in line with one another, tobacco sufficient to fill the bore of tubular member 12 above cap 32 up to and above bore 8. By giving cap 30 a right hand rotation, section 25 will be rotated, as will sections 24, 23, 22 and 21, but section 20 will be caused to remain non-rotatable due to the socketlike engagement of walls 14 with the decagonal edge of disc 17, whose series of walls 18 are sized and shaped to slide longitudinally but not laterally of walls 14 and the frictional engagement of tubular member 12 with the wall of opening 16. Due to the non-rotation of section 20, the remaining sections will unscrew one from the other and thereby rise longitudinally of tubular member 12. The user of the present pipe will, according to his particular taste, determine by experience the position at which he desires the burning portion of the tobacco 10 to be positioned within or above the bore 8 of bowl 5. After the determination of such a point, the burning portion of tobacco may be kept at that position by rotating member 30 and thereby elevating disc 17 and the tobacco supported thereon. The position of the burning tobacco within the bore 8 or thereabove determines the amount of oxygen which is to be supplied thereto and it has been found by experience that the tobacco burns equally as well above the bore 8, as shown in Fig. 2, or within the bore 8, whichever may be desirable.

The user of the pipe structure, by drawing 70 through bore 2 and applying the flame to the tobacco within bore 8, will cause the ignition thereof, due to the air drawn through bore 8 past tapered section 7, chamber 6 and the bore of stem portion 4. The projections 9 are spaced 75

apart to provide an opening therebetween for the passage of the smoke.

Due to the meerschaum cap 32, disc 17 can be elevated up to the top of tubular member 12 and the tobacco thereby consumed down to the cap 5 32. Said cap 32, being absorbent and heat insulating, will prevent the disc 17 from sticking to the walls 14 of tubular member 12, inasmuch as the tars and residues from the burnt tobacco are 10 completely absorbed by the cap 32. Further, tubular member 12 being formed from a lightweight metal, will remain cool due to the protection of cap 32 and the tobacco thereon and will therefore readily conduct heat from the smoke by the 15 periphery thereof.

The pipe structure as herein described and shown upon the accompanying drawing is capable of considerable modification but, however, any such modifications as come within the scope 20 of the appended claims are deemed to be a part of the present invention.

I claim:

1. An improvement in smoking pipe bowl assemblies comprising a tubular member forming 25 a bowl portion, a stem connected to the base and bore of said bowl, said bowl having an opening formed through the base thereof, a tube forming a tobacco reservoir having the bore thereof in line with the bore of said bowl detachably positioned within and spaced from said bore and 30

extending through said opening, rotatable tobacco raising and lowering means positioned through the bore of said tube, said tube having an annular flange formed upon and extending laterally from one end of said tube and seated against the outer face of said bowl, a second tube 5 rotatably mounted within said first tube and connected to said rotatable means for operating the same, said second tube having an annular flange 10 slidably seated upon the inner face of said first tube flange and a cap detachably connected to said second tube closing one end thereof and slidably contacting the outer face of said first tube flange. 15

2. An improvement in smoking pipe bowl assemblies comprising a pipe bowl, a stem connected to the wall of said bowl, a portion of the bore of said bowl being enlarged to form a chamber connected to said stem, an opening formed through the base of said bowl, a tube forming a 20 tobacco reservoir detachably mounted within said opening and extending through said chamber in spaced relationship to the side walls thereof to within a short distance of said bore, a flange formed at one end of said tube closing said base 25 opening and retaining said tube from said bore and means rotatably carried by said flange for raising and lowering tobacco therein and closing one end of said tube.

HAROLD T. BLUM. 30
